Edwin P. Coates ATTORNEY.

UNITED STATES PATENT OFFICE.

GILBERT A. BENNETT, OF COLUMBUS, OHIO.

GOLF-BAG SUPPORT.

Application filed May 3, 1924. Serial No. 710,943.

My invention relates to golf bag supports and has to do particularly with the provision of a detachable device for supporting golf club bags of standard construction in an upright position.

In the past, when playing golf with the standard equipment, it has been the usual practice, when playing without the assistance of a caddy, to drop the bag lengthwise of the ground, make the stroke, regain the bag and proceed along the course. The inconvenience of this practice will appear when it is considered that in the average golf game this will involve stooping to pick up the bag some hundred or more times. Furthermore, a golf club is a very delicate device and the slightest imperfection in balance will make it entirely worthless and the throwing of the bag to the ground, together with the stumbling over same by player and caddy, has hitherto not only resulted in damaged bags but has also resulted in damaged and broken golf clubs.

My invention has to do primarily with the provision of a simple, efficient and inexpensive means for eliminating the heretofore mentioned annoyances and inconveniences attending golf playing which comprises a device which may be readily attached to the golf bag whereby the bag may be made to stand upright upon the ground.

One of the objects of my invention is the provision of a device which may be attached to or detached from the bag with a minimum of time and effort and which, when attached, may be inserted in the ground to retain the bag in upright position. The result is that the bottom of the bag will be reinforced and the bag positioned upright instead of being carelessly thrown to the ground, thus not only making it very convenient to draw and replace clubs, dispose and regain the bag but also conserving the appearance of the bag and reducing the liability to injury and damage of the clubs to a minimum.

Another object of my invention contemplates the provision of a device of special design whereby it may be attached to bags of varying sizes without change.

A further object of my invention is the provision of a support as a single integral unit. The result is that it is cheap and simple to manufacture and light, a very important feature when it is considered that

during a game, the bag is carried great distances.

A still further object of my invention has to do with the provision of a resilient support that may be contracted and placed in the base of a standard golf bag and then released with the result that the support will be held in place due to its own resiliency.

Other objects and advantages of this invention will be apparent as this description progresses and will be brought out in the appended claims. The invention is clearly illustrated in the accompanying drawings wherein similar characters of reference designate similar parts and wherein:

Figure 1 is a vertical section of a golf bag of standard construction showing, in full lines, the preferred form of my novel support attached thereto.

Figure 2 is a perspective view of the bottom of the structure shown in Figure 1 and showing the manner of leaving one end of the support open.

Figure 3 is a plan view of my novel bag support showing the manner of arranging the prongs inside the normal circumference of the support.

Figure 4 is a fragmentary vertical section of a modified form of my invention wherein the prongs are attached to the reinforcing ring in the bottom of the bag.

Figure 5 is a fragmentary vertical sectional view showing a modified method of attaching the supporting device to the bag.

In the drawings, my invention is shown in its preferred form as comprising a horseshoe or C-shaped resilient member 1 having a plurality of downwardly extending offset prongs 2. The prongs 2 may be of any number and arranged in any position, but as shown in Figure 3, I preferably arrange the prongs inside the normal circumference of the open ring member 1.

The member 1 is preferably made of a resilient material and may obviously be made smaller in diameter by moving the prongs at the open end of the ring toward each other. This member 1 is designed to be inserted in the base of a standard golf bag which bottom or base may be designated 3. Such golf bags are usually provided with leather or cloth sides 4 and a leather cup-shaped base 5.

The method of constructing a standard golf bag of this type consists in bending the leather base 5 about a reinforcing ring 6 in

such a manner as to secure the leather or cloth sides of the bag 4 between the abutting surfaces of the leather base 5, as is shown at 7 in Figure 1.

As is apparent, this method of constructing the bag results in the forming of a cavity or circular depression in the bottom of the bag, and it is this point of construction which I utilize in my invention by providing a resilient member 1 designed to removably fit in this cavity formed by the cup-shaped bottom 5. The ring 1 is designed to be contracted and placed in the cavity in a plane above the ring 6, so that when released, it will engage the bag above the ring and thus be held in place.

While under all ordinary conditions, my supporting device will be sufficiently resili-
ent to be held in place in the bottom of the
golf bag, yet it will be obvious that in some
particular cases the resilient member 1 could
not be positioned above the ring member 6.
Therefore, in order to hold the member 1
securely in place under all conditions, I
have provided a plurality of projections or
rivets 8. The purpose of these projections
is to indent or pierce the cloth or leather bag,
as shown at 8 in Figure 1, and thus assist
in retaining the support 1 in position in
addition to the resilient restraining effect
between the outer circumference of the sup-
port and the ring 6.

An additional method of fastening the
resilient member 1 in place is to provide a
suitable means for fastening the device per-
manently to the bag, as for instance, by using
bolts or rivets as shown at 9 in Figure 5.
A modified form of support is illustrated
in Figure 4 wherein the reinforcing ring
member 6 is shown as being provided with
integral downwardly depending prongs 10.
Such a structure would not be removable,
however, and the specially designed ring
would have to be incorporated in the bag
preferably when originally constructed.

It will thus be seen that I have provided
a novel, simple and very compact device which
is designed to be removably applicable to the
base of the golf bag and which device is
of sufficient resiliency that it can be applied
to and be retained in position by golf bags
of varying diameters. It will further be
obvious that my simple, resilient support can
be quickly applied to the bag at any time

when its use is desired for holding the bag 55
upright upon the ground, and which de-
vice may be quickly removed when not
needed.

Having thus described my invention, what
I claim is:

1. A golf bag support comprising a resili-
ent open ended annular member adapted to
removably engage the bottom of the golf
bag, and a plurality of prongs carried by
and projecting downwardly from said 65
member.

2. A golf bag support comprising an open
ended member of sufficient resiliency to re-
movably engage the bottom of golf bags
of varying diameters, and means projecting 70
downwardly from said member for support-
ing the bag in position.

3. In combination with a golf bag hav-
ing a bottom reinforcing ring, a resilient
member having downwardly depending 75
prongs and adapted to engage the bottom of
the bag above said reinforcing ring.

4. A golf bag support comprising a resili-
ent ring shaped member and prongs depend-
ing from said ring shaped member. 80

5. A golf bag support comprising a ring
shaped member adapted to be positioned
adjacent the bottom of the golf bag, said
support being held in position by means of
the lateral pressure of the support against 85
the walls of the golf bag, and prongs de-
pending downwardly from said support and
adapted to engage the supporting surface.

6. In combination with a golf bag of a
support resiliently engageable with the golf 90
bag for holding the support in position, and
prongs projecting downwardly from said
support for supporting the bag in position.

7. In combination with a golf bag of a
support resiliently engageable with the golf 95
bag for holding the support in position and
means forming a part of said support for
retaining said support in position independ-
ently of said resilient action, and means
carried by said support for engaging said 100
support with the supporting surface.

8. A golf bag support formed as a unit
comprising a ring shaped member and down-
wardly depending prongs positioned within
the normal circumference of said ring. 105

In testimony whereof I affix my signa-
ture.

GILBERT A. BENNETT.
